7 Claims.

(Cl. 22—2)

This invention relates to that type of casting machine which is used for casting stereotype printing plates, mostly for newspaper work, wherein the matrix is set in clips, automatically stripped from the plate and the machine is ready for the casting of another plate without any additional setting of the matrix on the part of the operator. Machines for this purpose are commonly used in newspaper work particularly 5 in black and white printing.

The principal objects of this invention are to secure accurate register in black and white printing, but particularly in color printing; to provide a method whereby in casting a number of 10 plates from a single setting of a matrix the difficulty usually encountered in maintaining accurate register is eliminated; to provide a construction in which the natural tendency for the matrix to creep little by little at each casting 15 will be corrected so that the cumulative movement of the matrix in the casting of a plurality of plates cannot occur because the correction is made automatically after the casting of each plate; and to provide for the automatic registration of the matrix after each casting operation so 20 that the matrix will always be in proper registration at the casting of each plate, whereby the matrix will be in exactly the same position when the last plate is cast as it will be at the casting of the first or any intermediate plate.

30 Other objects and advantages of the invention will appear hereinafter.

Reference is to be had to the accompanying drawings, in which—

35 Fig. 1 is a plan, partly in section, showing the matrix clamping arrangement with a preferred embodiment of this invention applied thereto and with the matrix bars and clips in proper position for locating the matrix before the first cast;

40 Fig. 2 is a similar view showing the next step in the clamping of the matrix and showing the registering pins properly positioning the matrix;

45 Fig. 3 is a similar view showing the matrix fully clamped against the casting box ready for the cast, with the registering pins withdrawn so that any slight movement of the matrix will not injure the registering holes in the matrix;

50 Fig. 4 is a similar view showing the position when the casting box is being moved away from the cast plate after the casting operation and the matrix is being stripped while the registering pins are re-locating the matrix, and

55 Fig. 5 is an elevation, as indicated by the arrow 5 of Fig. 1, of the matrix bar and clips with this invention applied thereto.

The invention is shown as applied to a casting box which comprises a back 1 and an upright cylinder or core 13. The back is movable toward and from the cylinder, and the cylinder is

5 rotatable or otherwise movable to free or discharge the plate cast between them. The invention is applicable, of course, to casting boxes of this general type whether they are arranged vertically or otherwise, and in fact to those in which the cylinder is bodily movable instead of the back.

The back is shown as provided with a matrix bar 2 mounted in bearings 3 carried by the back. The matrix bar is provided with top and bottom studs 5 arranged vertically and, in this case, they 10 oscillate in the bearings 3. At the top a torsion spring 7 is provided with one end attached to the top bearing 3 and the other end to the matrix bar. This spring is wound and tensioned so as to tend to keep the matrix bar in the position shown in Fig. 4. The usual matrix clip 8 is shown provided with studs 9 operating in slanting slots 10 in the matrix bar to clamp the matrix. The slots 10 are placed at an angle with 15 respect to the length of the bar 2, and provided with a large opening at the top. This permits the removal and replacement of the clip 8 as desired. The clamping member is used for properly clamping the edge of the matrix between the clip 8 and the matrix bar 2. These parts are 20 duplicated on the opposite edge. These features just described are old, and it is customary, in a machine of this kind, to provide means for properly adjusting the clamping action. It is to be 25 understood that this invention is applicable to a casting box so made, but these features are not 30 illustrated here as they are so well known.

35 Fixed to the top of the top stud 5 is a locking lever 11, one end of which is shaped to cooperate with a cam 12 secured to the cylinder 13. From 40 observation of Fig. 3 it will be seen that when the back 1 is moved toward the cylinder 13 the locking lever 11 engages the cam 12 during the motion of the back and before that motion is completed. The completion of the motion of the back into its final position, therefore, results in 45 swinging the locking lever 11 backwardly, taking with it the matrix bar 2, the clip 8, and also the matrix, the edge of which, of course, is gripped between the clip and the bar. This brings the matrix firmly against the back 1 so that it is 50 locked in proper position for the casting of a stereotype plate against it.

The other end of the locking lever 11 is provided with two notches 4 and 6 for cooperation 55 with a roller 14 which is mounted rotatably on a stud carried by the locking handle 15. This lever is pivoted to the back by a stud 19.

Referring now to Fig. 1, the back 1 may be 60 considered as away from the cylinder, but the matrix bar and clips are in proper position for locating the matrix before the back is moved into casting position. The roller 14 is now located in the outside notch 4 of the locking lever 11. It 65

will be understood that a similar arrangement is carried on the other side of the back. In this position there is a slight amount of clearance from one clip 8 to the other over the entire length 5 of the matrix. This permits the matrix to be slid into the clips easily in the proper place. When this is done the locking handle 15 is moved to the position shown in Fig. 2, so that the roller 14 engages the inside notch 6 of the locking lever, 10 and the clip 8 is moved toward the matrix bar 2 to lock the edge of the matrix between them.

Referring now to Figs. 2 and 5, it will be seen that a shaft 16 is carried in bearings on the matrix bar 2 and has secured to it a lever 17 and 15 pin arms 18. On the locking handle 15 is a cam projection 20 which engages one end of the lever 17 in this position and, on account of the motion of the locking handle 15 just described, rotates this lever 17 slightly in a counter-clockwise direction to the position shown in Fig. 2, so that the pin arms 18 move inwardly against the ends of the matrix locating pins 21. This forces these pins from the position shown in Fig. 1 to the position shown in Fig. 2 through previously 25 punched holes in the matrix, this action being resisted by a pair of springs 23. These pins have conical ends so that they will go through the holes in the matrix and, as the holes are the same size as the pins, they will register the matrix perfectly and bring the matrix into the proper position for casting the first plate.

However, before the plate is cast, the locking handles 15 are opened to the position shown in Fig. 4. In this position a projection 25 on the lever 17 comes to bear against the solid portion of the back, preventing further clockwise rotation of the shaft 16 and holding it in the position shown in Fig. 4. As the matrix bar 2 pivots around the center of the studs 5 the pins 21 are again projected through the holes in the matrix. Their ends enter recesses 22 in the clips 8. Afterward, as the casting back 1 moves further forward, the locking lever 11 cooperates with the locking cam 12 and the relative motion of these two parts permits the springs 23 to withdraw the pins 21. This leaves the matrix free to move except for the friction hold that the clips 8 exert against the matrix bar 2. This arrangement is provided because the contraction of the stereotype metal just after the pouring is one of the causes of the creeping of the matrix. The power exerted by this contraction is so tremendous that any attempt to hold the matrix firmly against creeping would result in the rupture of the matrix at the holding point and thereby destroy any possibility of relocating the matrix.

After the first plate is cast the casting back of course is drawn away from the cylinder and the parts take the position shown in Fig. 4, as stated. Here the pins 21 reengage in the holes of the matrix and any slight tendency of the matrix to move is corrected immediately after the casting operation by the insertion of these conically pointed pins and the matrix is brought back to its original position or re-registered. 65 Any number of castings may be made with this arrangement and the matrix is re-registered automatically after each casting and before the plate is removed. Therefore the last plate maintains as accurate a register as the first or any intermediate plate.

Having thus described my invention and the advantages thereof, I do not wish to be limited

to the details herein disclosed, otherwise than as set forth in the claims, but what I claim is:

1. In a stereotype plate casting box, the combination with a cylinder adapted to be turned on its axis and a casting back movable toward and from the cylinder, of registering pins carried by said back, a locking handle, and means operated by the locking handle for moving said registering pins into a position to register the matrix while the mold is open. 10

2. In a stereotype plate casting box, the combination with a cylinder adapted to be turned on its axis and a casting back movable toward and from the cylinder, of registering pins carried by said back, a locking handle, means operated by the locking handle for moving said registering pins into a position to register the matrix while the mold is open and means for withdrawing the said pins from the matrix as the mold is closed and for thereafter projecting the pins to a position to re-register the matrix before the mold is closed for the second casting. 15

3. In a casting box, the combination with a cylinder and a casting back movable toward and from the cylinder to form the mold for the plate, of means for holding the edge of a matrix provided with perforations, matrix pins adapted to pass through said perforations to register the matrix, a locking cam on the cylinder, a locking lever movably mounted on the back, means for moving said locking lever from one position to another, in one of which positions the locking lever engages the cam and moves backward as the back moves forward, and means connected with said locking lever for registering the matrix. 25

4. In a casting box, the combination with a cylinder and a casting back movable toward and from the cylinder to form the mold for the plate, of means for holding the edge of a matrix provided with perforations, matrix pins adapted to pass through said perforations to register the matrix, a locking cam on the cylinder, a locking lever movably mounted on the back, a handle for locking the back to the cylinder, means carried by the handle for moving said locking lever from one position to another in one of which positions the locking lever engages the cam and moves backward as the back moves forward, and means connected with said locking lever for registering the matrix. 40

5. In a casting box for newspaper printing plates, the combination with a cylinder and a back movable toward and from the cylinder, of a locking cam fixed on the cylinder, a locking lever pivotally mounted on the back and adapted to engage said cam, said locking lever having two recesses, a handle for locking the back in casting position, a cam projection on the locking lever, and means operated by the lever for registering the matrix, whereby the contact of said cam projection with said lever will operate the registering means as the back is closed. 50

6. In a plate casting mechanism, the combination of means for registering a matrix, means for casting a plate, a spring for withdrawing the registering means, and a cam for re-registering the matrix before casting the next plate. 65

7. A plate casting mechanism comprising a matrix and a cam and lever for automatically registering a matrix, withdrawing the registering means, and re-registering the matrix between the casting of each plate. 70
